UNITED STATES PATENT OFFICE

FRIEDRICH KLOPP, OF WALD, GERMANY

APPARATUS FOR HARDENING THE FLANKS OF SPINDLE AND WORM THREADS

Application filed March 6, 1930, Serial No. 433,777, and in Germany March 12, 1929.

This invention relates to an apparatus for hardening spindle- and worm threads and the like, in which the screw- and worm threads to be hardened are immersed up to the middle 5 of the spindle in the quenching liquid of a quenching tank and, continually rotated in said liquid, the flanks of the threads being heated above the surface of the quenching liquid by a pointed flame of an autogenous 10 or other suitable burner which engages by means of a fitted block with the thread of the spindle and is thus moved along the spindle.

An embodiment of the invention is illustrated by way of example in the accompanying 15 drawing in which:

Fig. 1 shows the apparatus in elevation partly in section.

Fig. 2 is a section on line 2--2 of Fig. 1.

On one end of a quenching tank *a* a bracket *b* is arranged in which a clamping chuck *c* is mounted, which is driven by a worm wheel *d* and worm *e*. The spindle *f*, the thread flanks of which have to be hardened, is clamped at one end in the clamping chuck *c* 25 and at the other end guided in a bearing *g*, fixed on the other end of the quenching tank *a*. The spindle *f* is immersed up to its middle into the quenching liquid in the tank *a*. In a bearing *h*, mounted on the end of tank *a* 30 on which the bracket *b* is arranged, an axle *i* is guided. On this axle *i* an arm *m* is loosely mounted which carries on its free end an autogenous burner *k*. The gas is supplied to the burner *k* from a gas pipe *n*, the cock in the gas pipe being controlled by a handle *o*. A fitted block *l* of the burner *k* engages with the thread of the spindle *f*.

The thread flanks of spindle *f* are hardened in that the burner *k* is moved along the spindle, when this spindle is being rotated, the flanks being successively heated to the desired temperature by the pointed flame from the burner *k* from one end of the spindle to the other end of the same and instantaneously quenched at the heated points.

For multi-thread spindles the burner *k* is constructed accordingly.

In order that at the end of the spindle 50 thread the burner *k* be automatically rendered ineffective, a stop or abutment may be pro-

vided against which the handle *o* of the cock in the gas pipe *n* strikes so that the cock is turned and the gas supply shut off. This stop might be constructed in such a manner that the block *l* of the burner *k* is simultaneously lifted out off the thread of the spindle *f*.

I claim:

An apparatus for hardening the flanks of the screw threads of spindles, worms and the like, comprising in combination a quenching tank, bearings in said tank adapted to hold and rotate the work of which the flanks of the screw threads are to be hardened, a guide axle extending along said tank parallel to 60 said bearings, an autogenous burner loosely mounted on said axle, and a fitted block on 65 said burner adapted to engage in the screw thread of the work and to automatically feed 70 said burner along said axle owing to the rotation of the work.

FRIEDRICH KLOPP.
